MARC O. ANTHONY, OF PHILADELPHIA, PENNSYLVANIA.

MANIFOLDING MECHANISM FOR TYPEWRITING MACHINES.

Application filed April 6, 1925. Serial No. 21,198.

My invention relates to equipment for typewriting machines, preferably those of the visible type, for effecting the production of multiple or duplicate copies of the original writing, without the necessity of employing independent, removably-positioned, carbon sheets. My present invention relates more particularly to a multiple ribbon attachment supported by and movable with the carriage, with the multiple ribbons disposed in proper relative position with respect to the usual ribbon of the typewriting machine whereby I am enabled to make duplicate impressions upon a plurality of work-sheets passing around and fed by the platen and properly located with respect to the other parts of the typewriting machine, (usually special form sheets, bills, and the like), from the blow struck by the type-bars upon the ribbon usually employed and located in the normal position with respect to said platen.

The main object of my invention is to provide a simple form of supporting frame for the multiple group of copying or duplicating ribbons, which frame may be self-contained and may be readily attached to and detached from the typewriting machine without otherwise affecting the use of the machine in any way, and without changing or affecting in any way the normal and usual operation of the typewriting machine whether my attachment is employed or not. If desired, the multiple ribbon carrier may be built into and form part of the usual traveling carriage.

A further object of my invention is to provide a multiple set of ribbons which may be wound upon and unwound from independent spools carried at opposite ends of the detachable frame; each spool receiving a group of superposed ribbons which are unwound from one spool and wound up on the other (and vice versa); which ribbons are independently guided so as to move past the printing point, and between which the superposed plies of a work-sheet, carrying forms, duplicate bills, or the like; normally presented to the paper guide-apron of the typewriting machine in fan-folded condition, may be passed around the platen. The several ribbons are preferably slightly spaced apart, so as to reduce, if not entirely

prevent, undue frictional engagement with the superposed plies of the work-sheet delivered by the platen and alternating with said ribbons.

A further object of my invention is to provide means for imparting a feed movement to said ribbons during the retractive movement of the carriage.

A further object of my invention is to provide tension means for the respective ribbons so that while they are relatively free to move for a feeding operation upon retraction of the carriage, they will be maintained at all times in a substantially taut condition so as to receive clean blows from the respective type-bars and produce the desired impressions upon the plies of the work-sheet underlying the same.

A further object of my invention is to provide a separating guide and support for the multiple ribbons disposed in position for engagement by the type-bars.

A further object of my invention is to employ a series of wires of relatively fine gage underlying the ribbons and between the plies of the work-sheet, which wires may be employed to split the folds of said work-sheet.

A further object of my invention is to provide means for partially weakening the folds of the fan-folded work-sheet so that said folds may be readily slit by the wires underlying the multiple ribbons.

And a still further object of my invention is to provide the typewriting machine with a paper guide-apron carrying means for slitting a continuous fan-folded paper web or work-sheet, so that the plies making up such fan-folded work-sheet may be properly separated into individual sheets for introduction between the superposed ribbons in order that they may occupy the proper relative position to receive the duplicate impressions from said ribbons by the action of the type-bars striking the platen.

These and other features of my invention are more fully described hereinafter; reference being had to the accompanying drawings, in which:—

Figure 1, is a plan view with certain parts broken away, of a typewriting machine of the so-called "visible" type, showing details of construction forming the subject of my present invention.

Fig. 2, is a side elevation of a portion of the typewriting machine, showing an end view of the movable carriage and the multiple ribbon supporting frame which I employ mounted thereon; such view showing also the paper guide-apron and one form of slitting means for the continuous fan-folded work-sheet within the scope of my invention.

Fig. 3, is a front elevation of a detail of construction, on a larger scale; such view being partly in section on the line III, III, Fig. 1, looking in the direction of the arrows.

Fig. 4, is a sectional elevation of one of the 15 guide rollers for the manifolding ribbons, taken on the line IV—IV, Fig. 3.

Fig. 4^a, is an inverted plan view, on a larger scale, of the guide roller shown in Fig. 4.

Fig. 5, is a diagrammatic plan view of the 20 guide and tensioning means for the superposed manifolding ribbons.

Fig. 6, is a plan view of a part of the manifolding ribbon-supporting frame; illustrating 25 a modified form of driving means for the manifold-ribbon-carrying spools.

Fig. 7, is a sectional elevation showing the 30 relation of the manifolding ribbons with respect to the superposed plies of the work-sheet passing between the same and the usual ribbon of the typewriting machine; showing also the separating or spacing means for the plies of the work-sheet.

Fig. 8, is a detached perspective view of a 35 portion of the means employed for spacing the plies of the work-sheet adjacent to the manifolding ribbons and one of the supports therefor.

Fig. 9, is an enlarged view, partly in section, of a portion of the spring actuated drum forming part of the means for effecting feed 40 movement of the manifolding ribbons.

Fig. 10, is a sectional view on the line X—X, Fig. 9.

Fig. 11, is a diagrammatic view of one of 45 the slitting members carried by the paper guide-apron for severing the plies of the continuous fan-folded work-sheet, and

Fig. 12, is a diagrammatic view illustrating 50 the position of the slitting members with respect to the plies of the fan-folded work-sheet; the latter being shown in section.

As hereinbefore stated, the main object of 55 my invention is to provide simple and adequate means for effecting multiple copying by the use of duplicating ribbons associated with a typewriting machine; the mechanism forming the subject of my invention being applicable to the so-called "visible" typewriting machines of the Remington or Underwood types.

In the drawings, the carriage of the machine is indicated generally at 1, and is the usual carriage found in the machines of commerce of the type mentioned, and operating

in the usual manner. Upon this carriage a frame 2 is mounted, which may comprise a front bar 2^a, underlying the front rail 1^a of the carriage and secured thereto by set screws 3, with shelf or table portions 2^b and 2^c, at opposite ends of said bar 2^a; and a bar 2^d, at the rear, disposed adjacent to the usual platen A which is mounted in the carriage 1 in the usual manner; such bar 2^d being detachably mounted on the table or shelf portions 2^b and 2^c, of said frame 2, and secured thereto by means of set screws 3^a.

Each of the table portions 2^b and 2^c is provided with a vertical post or stem 5 and 5^a, upon which ribbon spools 6 and 6^a are 80 mounted for rotation; each of such spools carrying a plurality of superposed ribbons indicated at 7, and being arranged for operative association with a worm wheel whereby they may be driven to impart feed movements to said superposed ribbons, as herein-after described.

Suitably journaled in bearings 8 carried by the bar 2^d, is a shaft 9 carrying worms 10 and 10^a, each arranged to mesh with a worm wheel mounted on the posts 5 and 5^a and associated with the ribbon spools 6 and 6^a. In one arrangement of my improved construction I propose to use a shiftable worm wheel indicated in Fig. 1, at 11. When this worm wheel is mounted on the post 5, as indicated in Fig. 1, and motion is imparted to the shaft 9, the worm 10, in mesh with said worm wheel, will cause the latter with the ribbon spool 6 to be 100 moved in the direction of the arrow *x*; rotating the spool 6 in the same direction and winding the superposed manifolding ribbons 7 thereon. When the ribbon spool 6 is substantially filled and it is desired to move the manifolding ribbons in the opposite direction, the worm wheel 11 may be manually shifted to the post 5^a for meshing engagement with the worm 10^a and upon movement of the shaft 9 in the same direction, motion will be imparted to the worm wheel and to the ribbon spool 6^a associated therewith, in the direction of the arrow *y*, so as to rotate the spool in the same direction, and wind the superposed manifolding ribbons thereon; the latter unwinding from the spool 6. When the spool 6^a is substantially filled, the worm wheel may be again shifted to the post 5 and the action will continue as indicated.

The shaft 9 carrying the worms 10 and 10^a is driven by a spring actuated drum at certain intervals during the operation of the typewriting machine, through the medium of suitable gearing, in the following manner:

Secured to the movable carriage 1, of the typewriting machine, preferably at the right hand side of the same, is a supporting bracket 12, having end projections 12^a 130

and 12^b, in which a shaft 13 is journaled; said shaft being mounted for rotation with a spring actuated drum 14. Carried by the shaft 13 and disposed at one end of this drum is a helical gear wheel 15, which meshes with a helical gear wheel 16, carried by the shaft 9. Clutching mechanism is disposed within a shell 17 at the end of the drum, which may comprise a notched 10 disk 18, fixed to the hub of the helical gear wheel 15, with rollers 18^a, disposed in said notches and adapted to impinge upon the inner surface of the shell 17, fixed to the drum 14 when the latter is turned in one 15 direction.

Externally, the drum 14 carries a cord 20, having one end fixed to the drum at 20^a, while the other end may be connected to the frame of the machine at 20^b. Within 20 the hollow space of the drum, a helical spring 21 is disposed; one end being fixed to the bracket projection 12^b at 21^a, while the opposite end is connected to the drum at 21^b. The relation of these parts is such 25 that when the carriage 1, is moving to the left during the normal period of writing, the cord is wound upon the drum; the latter being turned by the spring as it extends, and there being no motion of the helical 30 gearing. When, in the ordinary practice of operating the machine, the carriage is restored to the right end position to commence a line of fresh writing, rotation of the drum will be effected by the cord 20, and the clutching means will be brought into 35 action; coupling the drum with the shaft 13, carrying the helical gear 15, which gear will be turned and by it the helical gear 16, to rotate the shaft 9, which in turn 40 moves a ribbon spool through the medium of one of the worms 10 (or 10^a), meshing with the worm wheel 11. At the same time the spring 21 will be wound up; storing its tension. To avoid all back lash, the 45 gear wheel 15 is preferably engaged by a flat spring 22.

The shaft 9, as shown in Fig. 1, of the drawings and described above, carries two worms, 10 and 10^a, in proper relative position with respect to the axis of rotation of the ribbon-carrying spools 6 and 6^a. By having right and left hand worms, it will be possible, as described, to employ a single worm wheel which, after the ribbons 50 have been wound upon one spool, may be shifted with respect to the other worm so as to effect winding of the ribbons on the other spool. This is an obvious method of taking care of this condition, and is effective 55 for all purposes.

In lieu of this arrangement, however, each spool may be equipped with a worm wheel, diagrammatically indicated in Fig. 6, at 11^b, and in mesh with the respective worms 10 and 10^a and the shaft 9 may carry a clutch

sleeve 25, suitably splined thereto, which shaft, in turn passes through sleeves 26 and 26^a carrying the respective worms; such sleeves 26 and 26^a being disposed in suitable bearings 8^a. When it is desired to operate the spool 6 at the right hand side of the frame to wind the ribbons thereon, the clutch sleeve 25 is moved to the right, bringing its notched end 25^a into engagement with a similarly notched end of the sleeve 26 70 which carries the worm 10, as clearly shown in Fig. 5; similar movement of said clutch sleeve in the opposite direction, to cause its notched end 25^b to engage the similarly notched end of the sleeve 26^a carrying the 75 worm 10^a, will effect rotation of the spool 6^a, at the left hand side of the frame.

The ribbons 7, wound upon the spools; being piled or superposed upon each other, individually pass from the spool 6 around 80 guide pins 31, thence over rollers 32, thence across the face of the platen to other rollers 32^a, and around other guide pins 31^a, to the opposite spool 6^a. These guide pins and rollers are clearly shown in Figs. 1 and 6, 85 and while the rollers 32 (or 32^a) are free to move in one direction, as indicated by the arrows, they are held against movement in the opposite direction; such arrangement serving to maintain the ribbons in a taut 90 condition during the writing operation.

Referring to Fig. 1, and to the diagrammatic views, Fig. 5, showing the rollers 32 and 32^a disposed adjacent to the ribbon spools and over which the ribbons pass to 100 and from said spools in order that they may be directed across the face of the platen in printing position with relation thereto, it will be noted that the pins 31 and 31^a are so positioned with respect to said rollers as 105 to impart a relatively sharp bend to the ribbons and assist in providing the necessary friction in order that the ribbons may be taut at all times.

These rollers have on their lower ends 110 teeth 33 and 33^a, cooperating with spring controlled pins 34, as shown in Figs. 4 and 4^a, so that they may only turn in one direction; the rollers 32, in the direction of the arrows z, and the rollers 32^a in the direction 115 of the arrows z'. For instance, when the ribbon is winding up on the spool 6, the rollers 32 at the right are free to turn, while the rollers 32^a at the left are held against movement during this operation and the 120 ribbons are pulled across the face of the same. Consequently the ribbons passing from the spool 6^a around the pins 31^a and thence over the friction roller 32^a will be retarded at such point, so that the operation 125 of the spool 6 to wind the ribbons will draw the same across the printing point in a taut condition. When such ribbons are being wound on the spool 6^a, the conditions 130 are exactly reversed.

These rollers 32 and 32^a may be recessed for the reception of friction sleeves 35, of rubber or other suitable material, and are preferably mounted on pins 36, the lower 5 ends of which enter recesses formed in the shelf portions 2^b and 2^c, while their upper ends enter apertures formed in plates 37 and 37^a overlying the same; which plates carry the guide pins 31, and are held down by 10 the bar 2^b. In addition, the plates 37 and 37^a carry guide hooks 38 and 38^a, under which the manifolding ribbons pass just before reaching the rollers 32 and 32^a.

In the present instance, I have only indicated 15 a pair of duplicating ribbons for the purpose of reproducing impressions upon two plies of the work-sheet; the latter being presented in the form of a triple fan-fold, the top ply being arranged to receive 20 impressions from the usual ribbon B, carried by the typewriting machine, while the second and third plies are adapted to receive impressions from the duplicating ribbons.

In order that the duplicate sheets of the 25 fan-folded section may be presented in proper condition with respect to the duplicating ribbons, the folds of the same must be cut and for this purpose I may employ wire slitting members 40, of substantially 30 the character illustrated in Fig. 1, and in the diagrammatic view Fig. 11. These slitting members are of substantially the same character as those shown in my companion application filed March 20, 1925, Serial No. 35 17,072, and may comprise runs of wire arranged in the special form indicated in Fig. 11, including a loop or eye 40^a, an upward run 40^b diagonally disposed with respect to said eye and extending toward the left to a curved portion 40^c, thence downwardly, still to the left; in a diagonal direction at 40^d, to a curve 40^e, and thence horizontally to the right at 40^f, to a curved end 40^g, with a return portion 40^h, parallel to the 40 run 40^f, such return portion being rebent at 40ⁱ, into substantial contact with the portion 40^h, and extending at 40^k diagonally toward the run 40^d, and having a rebent portion 40^m for contact therewith. This slitting member is preferably made of wire circular in cross section, and the contacting portions referred to are preferably secured 50 together by a suitable soldering or brazing operation.

A paper guide-apron 45, over which the continuous fan-folded work-sheet passes, is clearly indicated in Figs. 1 and 2, and this may have guide-posts 46, for positioning the paper laterally; such posts having reduced 60 ends 46^a, adapted to pass through slots 47 in said apron whereby such posts may be laterally adjustable; being held in their adjusted positions by nuts 47^a, applied to the reduced and threaded ends 46^b of the same.

65 The slitting members may be secured to

the apron 45, by means of posts 50, having threaded portions 50^a, passing through the eyes of the same, into slots 51, formed in the plate, whereby lateral adjustment of said posts and consequently the position of the slitting members with respect to the folds of the fan-folded work-sheets is provided for. The opposite end of the slitting member provided with the slot between the runs 40^f and 40^h, is guided by the oppositely disposed posts 50^a, which are of the same character as those passing through the eyes 40^a. These slitting members are placed so that the diagonal portions 40^b and 40^e are arranged to engage the folded edges of the fan-folded work-sheet, and as the latter is fed forward during the operation of the typewriting machine, it will be automatically separated into independent plies. Provision is made for the support of a number of slitting elements, so that continuous fan-folded work-sheets of two, three, four or more plies may be taken care of.

The paper guide-apron is hinged at 55 to bars 55^a supported by a cross-bar 56 mounted on the carriage and forming part of the usual equipment. This guide-apron is supported in the position illustrated in Fig. 2, by means of spring fingers 57, having seats 57^a engaging the rounded ends 55^b of the bars 55^a.

The superposed plies of the work-sheet after the folds of the same have been separated by the slitters 40, are fed around the platen when the latter is turned during operation of the machine operated in the usual manner, and upon the type-bars striking the usual ribbon when the keys are depressed, duplication of the written matter will be effected upon the superposed plies of said work-sheet by the manifolding ribbons 7 disposed in proper relative position with respect to the usual ribbon of the machine.

In order that the plies of the work-sheet 110 may be separated so as to avoid undue frictional contact with the ribbons tending to displace the same, I preferably provide separating wires 60, which extend across the machine in front of the platen and are disposed below the manifolding ribbons. These wires are carried by arms 61, pivotally mounted at 62, to the shelf or table portions 2^b and 2^c, and these arms are supported at their ends nearest the platen by stops 61^a. The ribbons are prevented from rising by guide hooks 38 and 38^a depending from the plates 37 and 37^a overlying the rollers 32 and 32^a, under which guide hooks the ribbons pass to said rollers. The wires have their ends fastened in diagonal slots 63 formed in the ends of the arms 61, as shown in Fig. 7, and they may be retained in place by brazing or welding, as may be desired. These wires are preferably disposed in the 120

several planes indicated, and in lieu of the same, I may employ narrow blades with their upper edges set in similar planes.

Under some conditions these wires may be employed to slit the folds of the fan-folded work-sheet as the latter is fed to the platen, and in order that this may be accomplished, I preferably mount upon the paper guide-apron a series of rolls 65, 66 and 67, whose function is to change the direction of movement of the fan-folded work-sheet in its passage to the platen; such sheet passing first under the roll 65, then over the roll 66, and then under the roll 67. These changes in the direction of movement of the fan-folded work-sheet tend to weaken and break down the folded edges of the same which have been previously perforated in the preparation of such fan-folded work-sheet, so that when such folds are presented to the wires 60, in such partially weakened condition, the latter can complete the separation of the plies; the folds offering little resistance to the splitting action of the wires.

In the operation of the means for imparting feed movements to the superposed manifolding ribbons, illustrated in Fig. 6, it is manifest, of course, that while one of the spools is being positively driven the other must be released to permit the ribbons to unwind from the same. Under usual conditions the non-driven spool with its associated worm wheel would be locked by the worm, hence it is necessary to provide means whereby the non-driven spool can be free to rotate and permit the ribbons to unwind from the same. For this purpose I may provide engaging and disengaging means between the worm wheels and spools, which may comprise a circular rack carried by one of these members, to be engaged by a spring pin carried by the other member so as to permit this movement; the relation of the parts being such that while either spool may be driven in one direction by its worm wheel, it will be free to turn in the opposite direction independently of the worm wheel. In lieu of this, the worms and worm wheels may be replaced by helical gearing.

The continuous fan-folded work-sheet, which may contain bill or other forms, is fed to the platen in the manner indicated in Fig. 2, and the writing is effected thereon in the manner common to typewriting machines. As each form is brought into position for the first line of fresh matter, the previously filled out form is to be removed from the continuous superposed sheets. To facilitate such removal, the rear bar of the frame 2, may be provided with a plate 69, having a cutting edge 69^a, against which the superposed sheets may be held and torn off by a quick movement; all of the plies being severed at one operation.

While I have referred to ribbons as the

means for effecting the duplication of the type impressions, upon underlying sheets of paper in superposed relation, the ribbons which I employ are preferably of thin paper, coated with carbon on the surface for contact with the sheets to be duplicated. The paper of which these ribbons are made is preferably of a very tough character, that will stand the feed movements between the spools without stretch or damage thereto until the carbon surface has been used up.

I claim:

1. The combination, in a typewriting machine, of a pair of supplemental spools, a plurality of superposed duplicating ribbons carried by said spools, guiding means for said ribbons adjacent each spool, said guiding means including rollers movable in one direction only under the influence of the ribbon when moving in one direction, and means for operating said supplemental spools.

2. The combination, in a typewriting machine, of a pair of supplemental spools, a worm wheel for operative association with said spools, a worm meshing with said worm wheel, a plurality of superposed duplicating ribbons carried by said spools, guiding means for said ribbons adjacent each spool, said guiding means including rollers movable in one direction under the influence of the moving ribbons, and means for operating said worm to move said supplemental spools.

3. The combination, with the movable carriage of a typewriting machine, of a frame supported thereby and movable therewith, a pair of supplemental spools journaled on said frame, a plurality of duplicating ribbons carried by said spools, guiding means for said ribbons; said guiding means including rollers movable in one direction under the influence of the moving ribbon and means for operating one of said supplemental spools to wind up the ribbons thereon when the carriage moves in one direction.

4. The combination, with the carriage of a typewriting machine, of a support, a pair of supplemental ribbon spools carried by said support, said spools supporting a plurality of superposed ribbons, a worm wheel for operative association with said spools, a worm for engagement with said worm wheel, a shaft carrying said worm, a spring roller operatively connected to the carriage, gearing connecting said spring roller with the worm shaft, said spring roller being wound when the carriage moves in one direction during the writing operation to store up energy in the spring, and turning in the opposite direction under the influence of the spring when the carriage is retracted; the latter movement of said spring roller operating the gearing between the same and the worm-shaft whereby said worm-shaft may

be turned to move one of the spools and wind the superposed ribbons thereon.

5. The combination, with the carriage of a typewriting machine, of a supplemental support, a pair of ribbon spools carried by said support; said spools supporting a plurality of superposed ribbons, a worm wheel for operative association with said spools, a worm for engagement with said worm wheel.
- 10 a shaft carrying said worm, a spring roller mounted on the carriage, gearing connecting said spring roller with the worm-shaft; said spring roller being turned in one direction when the carriage moves during the writing operation by energy in the spring stored during movement of carriage to the right, and turning in the opposite direction by the cord which stores energy in the spring when the carriage is retracted; the latter movement of said spring roller operating the gearing between the same and the worm-shaft whereby the said worm-shaft may be turned to move one of the spools and wind the superposed ribbons thereon.
- 15 6. The combination, in a typewriting machine, of a series of superposed duplicating ribbons disposed in printing relation with respect to the platen, spools for said ribbons upon which they are wound in their superposed relation, and guiding means for the individual ribbons to and from the spools including friction rolls which may turn when the ribbons are moving in one direction and are normally inactive when the
- 20 30 35 40 45 50 55 60 65 70 75 80 85 90 95 100 105 110 115 120 125 130
- ribbons are moving in the opposite direction for restraining movement of the ribbons in order that they may be maintained in taut position at the printing point.
7. The combination, in a typewriting machine, of a series of superposed duplicating ribbons disposed in printing relation with respect to the platen, spools for said ribbons upon which they are wound in their superposed relation and guiding means for the individual ribbons to and from the spools including rolls adjacent each spool and turning in one direction only for restraining movement of the ribbons as they are unwound from one spool in order that they may be maintained in taut condition at the printing point.
8. In a typewriting machine, the combination of a series of duplicating ribbons, spools upon which said ribbons are wound in superposed position, a series of friction rollers over which the individual ribbons are led, and pins disposed in fixed position with respect to said rollers around which the ribbons may pass whereby a bend is imparted to said ribbons to retard movement of the same in one direction; said friction rollers being held against movement when said ribbons are pulled across the face of the same in one direction.
9. In a typewriting machine, the combi-

nation of a series of duplicating ribbons, a pair of spools upon which said ribbons are wound in superposed position; said ribbons extending between said spools in printing relation with respect to the platen, a series of friction rollers over which the individual ribbons are led, and pins disposed in fixed position with respect to said rollers around which the ribbons may pass whereby a bend is imparted to said ribbons to retard movement of the same in one direction; the friction rolls adjacent the spool from which the ribbons are unwinding being held against movement when said ribbons are pulled across the face of the same during such unwinding operation.

10. The combination, in a typewriting machine, of a series of duplicating ribbons, a pair of spools around which said ribbons are wound in superposed relation, a series of guide rollers disposed adjacent to each of said spools, a pin disposed adjacent to each of said guide rollers whereby a bend may be imparted to the ribbons, and means for holding each set of rollers against movement in one direction; the ribbons when moving in one direction causing one set of said rollers to turn and pulling across the face of the other set.

11. The combination in a typewriting machine, of a series of duplicating ribbons, a pair of spools around which said ribbons are wound in superposed relation and extending across the platen in printing relation, a series of guide rollers disposed adjacent to each of said spools, a pin arranged adjacent to each of said guide rollers whereby bends may be imparted to the individual ribbons, and means for holding each set of rollers against movement in one direction comprising teeth on said rollers and spring pawls engaging the same; the ribbons when moving in one direction causing one set of said rollers to turn and pulling across the face of the other set.

12. The combination, in a typewriting machine, of a platen, means for moving work-sheets in superposed relation around the platen, a series of manifolding ribbons interleaved with said superposed work-sheets, and a series of wires adjacent to the manifolding ribbons for spacing the plies of the work-sheets.

13. The combination, in a typewriting machine, of a platen, means for moving work-sheets in superposed relation around the same, a series of superposed manifolding ribbons interleaved with said work-sheets and extending across the face of the platen longitudinally of the same, spools for said ribbons upon which they are wound in superposed relation, means for moving either of said spools to wind up said ribbons thereon, and spring motor means operative when the carriage is retracted for actuating said

means to effect said winding movement of the spools.

14. The combination, in a typewriting machine, of a platen, means for moving work-sheets in superposed relation around the same, a series of superposed manifolding ribbons interleaved with said work-sheets and extending across the face of the platen, a pair of spools upon which said manifolding ribbons are wound in superposed relation, means for imparting movement to said spools in different directions alternately to wind up said superposed ribbons alternately upon said spools, and spring motor means operative when the carriage is retracted to commence the printing operation for actuating said means to effect said winding movement of either spool.

15. The combination, with the carriage of a typewriting machine, of supplemental ribbon-carrying spools mounted thereon, a plurality of manifolding ribbons in superposed relation mounted on said spools, means for moving the plies of a work-sheet in interleaved relation with respect to said ribbons, means for effecting movement of the ribbon spools by movement of the carriage, a series of wires extending across the platen adjacent to the manifolding ribbons for spacing the plies of the work-sheet, and movable supports for said wires.

16. The combination, with the carriage of a typewriting machine, of supplemental ribbon-carrying spools mounted thereon, a plurality of manifolding ribbons in superposed relation mounted on said spools, means for moving the plies of a work-sheet in interleaved relation with respect to said ribbons, means for effecting movement of the ribbon spools by movement of the carriage, a series of wires extending across the platen adjacent to the manifolding ribbons for spacing the plies of the work-sheet, and a pair of hinged supports for said wires.

17. The combination, with a typewriting machine having a platen and means for feeding a continuous fan-folded work-sheet to said platen, of a pair of supplemental spools, a plurality of superposed manifolding ribbons carried by said spools, and a series of fine wires extending lengthwise of the platen below said ribbons and serving to slit the folds of said work-sheet in order to present the latter in separated plies to the manifolding ribbons; said wires serving also to space the plies of the work-sheet with respect to said ribbons.

18. The combination, in a typewriting machine, of a platen, means for moving a plurality of work-sheets in superposed relation around the same, a series of manifolding ribbons interleaved with said superposed work-sheets, a pair of spools for said ribbons, and sets of guide rollers adjacent each ribbon spool, each set of rollers being ar-

ranged to turn when the ribbons are being wound upon the spool adjacent thereto, and held against turning movement when the ribbons are unwound from the spool adjacent thereto.

19. The combination, in a typewriting machine, of a platen, means for moving work-sheets in superposed relation around the same, a series of manifolding ribbons interleaved with said superposed work-sheets, a pair of spools for said ribbons, sets of guide rollers adjacent each ribbon spool, each set of rollers being arranged to turn when the ribbons are being wound upon the spool adjacent thereto, and held against turning movement when the ribbons are unwound from the spool adjacent thereto; each of said rollers having toothed ends, and spring-controlled pins engaging said teeth.

20. The combination, with the platen of a typewriting machine, of a guide-apron disposed at the rear of said platen and extending diagonally above the same and over which a continuous fan-folded work-sheet may be fed to said platen, and slitting members for the folds of said work-sheet detachably supported by said guide-apron.

21. The combination, with the platen of a typewriting machine, of a guide-apron, disposed at the rear of said platen and extending diagonally above the same and over which a continuous fan-folded work-sheet may be fed to said platen, and adjustable slitting members for the folds of said work-sheet detachably supported by said guide-apron.

22. The combination, with a typewriting machine, of a platen, a guide-apron disposed rearwardly of said platen over which a continuous fan-folded work-sheet may be directed to said platen, and a series of rollers disposed in substantial alignment, with one surface in the same plane, carried by said guide-apron around which the fan-folded sheet may be passed in two directions whereby flexure of the same in opposite directions is effected to weaken the folded edges of the same.

23. The combination, with a typewriting machine, of a carriage, a pair of supplemental ribbon spools carried by the same, a series of ribbons in superposed relation wound on said spools, a worm wheel in operative relation each spool, a worm in operative relation with each worm wheel, a driven shaft, sleeves mounted on said shaft and supporting said worms, and a clutching sleeve longitudinally movable on the shaft for operative engagement with either of said worm-carrying sleeves.

24. The combination, in a typewriting machine, of a series of superposed duplicating ribbons disposed in printing relation with respect to the platen, spools for said ribbons upon which they are wound in their

- superposed relation, and guiding means for the individual ribbons to and from the spools including friction rolls normally inactive under one condition for restraining movement of the ribbons in order that they may be maintained in taut position at the printing point and pins adjacent said spools for abruptly changing the direction of movement of said ribbons.
- 10 25. The combination, in a typewriting machine, of a series of superposed duplicating ribbons disposed in printing relation with respect to the platen, spools for said ribbons upon which they are wound in superposed relation, and guiding means for the individual ribbons to and from the spools including sets of friction rolls adjacent each spool for restraining movement of the ribbons as they are unwound from a spool in order that they may be maintained in taut condition at the printing point and pins adjacent said spools for abruptly changing the direction of movement of said ribbons.
- 15 26. The combination, in a typewriting machine, of a platen, means for moving work-sheets in superposed relation around the same, a series of superposed manifolding ribbons interleaved with said work-sheets and extending across the face of the platen, a pair of spools upon which said manifolding ribbons are wound in superposed relation, means for imparting movement to said spools in different directions alternately to wind said ribbons alternately upon said spools, spring motor means operative when the carriage is retracted to commence the printing operation for actuating said means to effect said winding movement of the spools, and guiding means for the ribbons to and from the spools effective to restrain unwinding movement of said ribbons; said means including friction rolls and pins adjacent said friction rolls for effecting an abrupt change in the direction of movement of said ribbons.
- 20 27. The combination, in a typewriting machine, of a platen, means for moving work-sheets in superposed relation around the same, a series of superposed manifolding ribbons interleaved with said work-sheets and extending across the face of the platen longitudinally of the same, spools for said ribbons upon which they are wound in superposed relation, means for moving either
- of said spools to wind said ribbons thereon, spring motor means operative when the carriage is retracted for actuating said means to effect said winding movement of either spools, and guiding means for the ribbons to and from the spools effective to restrain unwinding movement of said ribbons.
